SHOE FLEXING MACHINE

Jack Faber and Gilbert R. Faber, Millersburg, Pa.

Application February 17, 1947, Serial No. 729,158

3 Claims. (Cl. 12—41.1)

1

This invention relates to shoes and boots for individuals and more particularly to flexing of their soles to make them fit more comfortably on the wearer.

It has been customary to flex and bend the soles intended for shoes before they have been applied and sewed to the uppers, at the factory. This is done to make them bend easier on the walker's feet, and while partially successful, it has not met the need adequately. This is because the assembly and sewing of the shoes produced an added stiffness to the shoes which the original flexing did not provide for, and therefore did not successfully anticipate.

This invention therefore was developed to meet this need by providing a machine that would take the finished and completed new or resoled shoe and flex it sufficiently to meet the needs of the wearer, at the time he is ready to wear it in actual service.

Therefore, it is an object of this invention to provide a new and improved shoe flexing machine that will avoid one or more of the disadvantages and limitations of the prior art.

Another object of the invention is to provide a new and improved flexing machine that will enable the flexing of a shoe to be done readily with it after the shoe is completely made up and commercially ready for the market and the user to put on.

A further object of the present invention is to provide a new and improved flexing machine for shoes that will have features of adjustability, compactness, convenience in its use; and be economical to build and produce for practical use.

Other objects will become apparent as the invention is more fully set forth.

For a clearer understanding of the invention and the objects thereof, reference is made to the attached drawings, and the description following. These together present the invention in a particular form by way of example, while the claims emphasize the scope of the invention.

In the drawings:

Figure 1 is a plan view of a shoe flexing device embodying this invention;

Figure 2 is an end view taken along lines 2—2 of Figure 1, and

Figure 3 is a sectional view taken along line 3—3 of Figure 2.

Similar reference numerals refer to similar parts throughout the drawings.

In the construction of this particular form shown, a shoe flexing machine consists of a framework 10 on which the side walls 11, top sur-

2

face or table 12 and bottom 13 are erected. A motor 14 is provided with shafts 16 running horizontally from each end. The shafts 16 have cross-head wheels 18 and 19 fastened to their end portions and arranged to adjustably hold cross heads 15 and 17 positioned on connecting rods 20 and 21 by studs 30. The wheels 18 and 19 are keyed to the shafts 16 or otherwise held to enable them to rotate with each other. The connecting rods 20 and 21 are connected with pushers 23 that are operated in guides 22 fastened to the framework 10 and reciprocate in a straight line. The cross-head wheels 18 and 19 are attached to the connecting rods 20 and 21 by cross-heads 15 and 17 which operate in slots 24 so they can vary the length of the stroke, of the rods 20 and 21. The pushers 23 are surmounted by a flexing plate 25 having a number of rollers 26 arranged along its upper surface and adapted to make contact with the lower surface of the sole of a shoe 36 held on the table 12. A clamp 27 has a block 28 insertable in each shoe 36 to be flexed, and fastening the heel to the table so it will be rigidly placed. A heel plate 29 presses against the back of each shoe to provide for a positive positioning of the shoe at that part. This heel plate is adjustable horizontally on the table 12 by means on a tongue 31 held in the slot 32 arranged therefor.

The purpose of the adjustment of the heel plate 29 is to permit the flexing plate 25 to be placed under the shoe sole in the most appropriate location for the work to be done. The block 28 holding the shoe to the table extends over the heel leaving the sole half free and open to be operated on. The flexing plate 25 is brought up against this sole and pushes up against it as it reciprocates. This bends the sole up through an angle sufficient to flex it and ordinarily allow it to drop back, but where the resiliency of the material of the sole is not enough to provide for this, the block 28 is used with a metal tongue 35 extending from it towards the toe of the shoe to give sufficient resiliency to do so. This does not interfere with the general flexing of the sole but in fact protects it against cracking. The diameters of the rollers 26 are spaced about $\frac{1}{8}$ " apart which is enough to permit the sole to be bent easily and without untoward rubbing of the shoe to mar its appearance.

It can be appreciated that the shoe may be readily placed on the table 12 of the machine and clamped in position, and the amount of flexing adjusted to suit the extent of flexing to be made on the shoe through the adjustment on the cross

head wheels. If a pair of shoes are to be flexed at the same time, they can be done on the machine using both clamps, heel plates and flexing plates at the same time on the same table. In this way the flexing for both shoes is the same and controllable to any extent desirable.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention, what is claimed is:

1. A shoe flexing machine of the class described comprising in combination, a framework having a table formed at its upper portion for supporting a shoe thereon, said table having a slot therein, a roller flexing plate positioned over said table slot and fastened at one end to said table, a heel plate positioned on said table for locating a shoe in predetermined relationship with said slot, a clamp for holding the shoe against the table and heel plate, a pusher oscillating up and down in said slot to raise and lower said roller flexing plate, and means for operating said pusher.

2. A shoe flexing machine of the class described comprising in combination, a framework having a table formed at its upper portion for supporting a shoe thereon, said table having a slot therein, a roller flexing plate positioned over said table slot and fastened at one end to said table, a heel plate positioned on said table for locating a shoe

in predetermined relationship with said slot, a clamp for holding the shoe against the table and heel plate, a pusher oscillating up and down in said slot to raise and lower said roller flexing plate, means for operating said pusher, and adjusting means attached to said pusher for regulating its amount of travel in said slot.

3. A shoe flexing machine of the class described comprising in combination, a framework having a table formed at its upper portion for supporting a shoe thereon, said table having a slot therein, a roller flexing plate positioned over said table slot and fastened at one end to said table, a heel plate positioned on said table for locating a shoe

in predetermined relationship with said slot, a clamp for holding the shoe against the table and heel plate, a pusher oscillating up and down in said slot to raise and lower said roller flexing plate, means for operating said pusher, adjusting means attached to said pusher for regulating its amount of travel in said slot, said heel plate being adjustably attached to said table to regulate the amount of the shoe sole being flexed.
